UNITED STATES PATENT OFFICE.

GEORGE ALEXANDER WETTENGEL, OF ST. LOUIS, MISSOURI.

SMELTING-FURNACE.

No. 901,405.

Specification of Letters Patent.

Patented Oct. 20, 1908.

Application filed August 13, 1907. Serial No. 388,325.

To all whom it may concern:

Be it known that I, GEORGE ALEXANDER WETTENGEL, a citizen of the United States, residing in the city of St. Louis and State of Missouri, have invented certain new and useful Improvements in Smelting-Furnaces, of which the following is a specification.

This invention relates to certain new and useful improvements in smelting furnaces, and the object is to provide a rotatable smelting furnace to facilitate charging the ore into the retorts, discharging the residue after smelting, and recovering the metal from the ore smelted therein.

The peculiarities of my invention will be hereinafter pointed out and claimed.

In the accompanying drawings in which like reference letters indicate corresponding parts, Figure 1 represents a front view of a smelting furnace, illustrating my invention with parts in section; and Fig. 2, a vertical cross section on the line X—X of Fig. 1.

I will describe my invention as applied to the smelting of zinc ore to which it is especially adapted, but it is not limited to this particular ore. The common method of smelting zinc ore is to mix it with a reducing agent, usually coal in suitable proportions, pack this mixture into suitable retorts of fire clay slightly inclined from the horizontal in a furnace, and subject the retorts to the heat of burning gas to smelt the ore and vaporize the zinc, which is condensed to the liquid form of molten zinc and drawn off at suitable intervals. These retorts, A, are about 4 feet long, 8 inches internal diameter and 1½ inches thick, closed at the rear, and supported at both ends in rows separately from each other, on a tile shelf

at the front and rear of the furnace, to allow the burning gas to play on all sides of them. Their front ends are left open, to allow of shoveling in the charge, and are then closed by the conical tubes, B, constituting the condensers, which extend beyond the furnace proper, and are each supported by a pivoted frame, C. The spaces between the retorts at the fronts are closed with fire clay, the joints between the retorts and con-

densers are made tight with loam and the small end of the condenser closed and vented. The vapor of zinc from the smelting ore is liquefied in the condensers, B, from which it is drawn into a trough, D, at about eight hour intervals, (or three times in 20 hours),

after which the retorts are cleaned out and recharged. The cleaning of the retorts is hard labor because of the heat and dirt. It requires much labor and considerable skill to shovel the ore mixture into the retorts in the common construction of smelting furnace.

In my construction the furnace, E, of fire brick, or other suitable material, forms the lining of a cylindrical metal drum, F, of any convenient length, and the retorts are mounted therein in the usual, or any suitable manner. Strong metal rings, G, encircle the drum at suitable intervals, and preferably support the furnace on rollers, H, mounted in suitable bearings, so that the furnace can be rotated by operating the pinion, I, meshing with the master gear, J, or otherwise. One roller is flanged and the other plain, to allow for expansion.

The furnace is supplied with air and gas, entering through suitable openings, K, preferably in the rear wall, the top and the bottom of the drum. The air pipes, L, extend along the outside of the drum, and are conveniently supported by the track rings, G, (or otherwise mounted so as to turn with the furnace), and are united at one end by an inlet pipe, M, Fig. 1, located axially with the track rings, G, and making a suitable rotatable joint with the blast fan outlet, N.

The gas pipe, P, Fig. 2, makes a similar axial joint with the end, Q, of the gas supply pipe, R, as shown. Branch pipes with regulating valves connect the air and gas pipes respectively, with the said inlet openings, K. Thus the furnace can be properly heated and rotated, and the air and gas regulated in any rotated position.

Above the furnace is a traveling crane, S, carrying a hopper trolley T, provided with slide-valve openings, t, matching the vertical rows of retorts, Fig. 1, when the furnace is rotated so that the front is upward. The crane and trolley can, therefore, readily charge the retorts from the supply hopper, U. The retorts, being on end when in charging position, can be completely filled; then the furnace is rotated downward to the right or left through one-quarter turn and the retorts brought nearly to a horizontal again. The retorts are then spaced or vented and the condensers are loamed at the joint and spaced at the mouth after stuffing. In practice, they are inclined downward

slightly, while the lower side of the condensers are kept nearly, or quite horizontal, for better collecting the molten zinc, which is readily delivered into the trough, D, by tipping the furnace, thus causing the molten metal to flow out of the condenser. A ladle, V, mounted on carrying wheels, receives the molten metal from the trough, D.

In a furnace of the ordinary construction, 10 the retorts are cleaned of residue by taking off the condensers, inserting a long pipe nozzle with a perforated end through which a small quantity of water is delivered to the back of the retort chambers successively. 15 The steam that immediately forms blows out the powderlike residue by its expansion in changing from a liquid to a gaseous form. A portion of zinc ore mixture forms a sticky slag on the bottom that can only be partly 20 removed by laborious scraping. This slag accumulates and reduces the size and efficiency of the retort and finally cuts holes clear through the retort, thereby necessitating its being replaced. In my rotatable furnace, 25 the condensers are taken off, and then the furnace is turned downward till the mouths of the retorts are over the pit, W, into which the loose residue is discharged from all retorts simultaneously. The cooling 30 action of the water is done away with and the consequent injury to the red hot retorts. Then the retorts are brought to an inclined position and the loam and any remaining residue are scraped out; the furnace 35 is then revolved until the retorts stand vertical with the open ends up, being brought to the top by about one-third revolution of the furnace, the recharging is effected as before described, and the furnace is rotated a 40 quarter turn, but with the front facing the opposite side, thereby bringing the slag residue uppermost in the retort chamber, where it will melt and drip down on the smelting charge and go out into the pit on the next 45 discharge. This reversal of the retorts in my furnace makes them practically self-cleaning, almost entirely avoids scraping, and increases the life of the retorts by using two sides of the retort so that the slag can- 50 not melt holes into it as easily as in the ordinary construction.

The average life of a retort is about thirty days. During that time it absorbs about 25 lbs. of zinc; but this absorption takes place 55 almost entirely during the first week of its use, and decreases in daily quantity as the retort gets older. Therefore, the longer the life of the retorts, the greater the output of the furnace, and the greater the percentage 60 of metal recovered becomes, compared with the quantity of metal in the ore, since they have taken up nearly their load of metal during the first week of use.

My rotatable furnace, with its self-clean-

ing and effective retorts, has a larger efficiency than the old form. 65

The temporary trough, D, is taken off before rotating. The track ring is preferably eccentric as to the drum, to avoid making the ring so much larger and yet embrace the 70 gas and air pipes.

The gas and air supply to each burner can be regulated as may be necessary, in order to maintain the temperature as required at different times during the smelting opera- 75

It will be understood that my rotatable furnace can also be used for smelting other metals than zinc, such as quicksilver ore, and it is also applicable to the manufacture of 80 coal gas.

Having thus fully described my invention, what I claim as new and desire to secure by Letters Patent is:

1. A rotatable smelting furnace having a 85 series of retorts transversely placed in a cylindrical drum, and adapted to rotate the open ends of the retorts upward for charging.

2. A rotatable smelting furnace comprising a suitable rotatable casing and a series of retorts transversely mounted therein, whereby said retorts may be turned downward for discharging. 90

3. A rotatable smelting furnace having retorts adapted to be reversed for self-cleaning, substantially as described. 95

4. A rotatable smelting furnace having retorts horizontally disposed, and regulated flame openings at the rear and above and below, for securing equal efficiency in either rotated position. 100

5. A rotatable smelting furnace having retorts in rows adapted to be turned upward for charging, in combination with a traveling hopper having regulated openings 105 matching said retorts, substantially as described.

6. A rotatable smelting furnace having retorts in rows adapted to be turned upward 110 for charging, in combination with an overhead traveling crane, a trolley hopper mounted thereon, and having regulated openings matching said retorts, and a main hopper for supplying said trolley hopper 115 with charging mixture.

7. A rotatable smelting furnace having retorts transversely disposed in a cylindrical drum, gas and air pipes carried by said drum and having practically concentric axial inlets, and means to rotate said furnace. 120

8. A rotatable smelting furnace comprising a cylindrical drum with suitable lining, 125 retorts transversely mounted therein, condensers, track rings encircling said drum, bearing rollers for said rings, and gas and air pipes having inlets concentric with said

track rings and connected with flame openings in said drum, substantially as described.

9. A rotatable smelting furnace having a series of retorts, adapted to be rotated so as 5 to invert the retorts, whereby the bottom of each retort may be made to serve as the top, and vice versa.

In testimony whereof I have affixed my signature in presence of two witnesses.

GEORGE ALEXANDER WETTENGEL.
